TELEPHONE REPEATER

Benjamin F. Lewis, Brooklyn, and Josiah Leverett Merrill, Jr., Jackson Heights, N. Y., assignors to American Telephone and Telegraph Company, a corporation of New York

Application September 1, 1933, Serial No. 687,874

16 Claims. (Cl. 179—170)

This invention relates to telephone repeaters, and more particularly to two-way telephone repeaters for use on irregular two-wire lines.

It is an object of this invention to obtain an effective repeater gain greater than would be permitted by the balance obtainable between the lines with which the repeater is to be used and their respective balancing networks.

A second object of the invention is to provide this gain with a minimum of distortion or other objectionable effects on the transmitted speech.

A further object is to minimize the possibility of harmful effects due to the presence of noise on the circuit.

In attaining these objects, the applicants make, in general, such modifications in an ordinary type of two-wire telephone repeater that there will always be sufficient attenuation in the singing path of circulating currents within the repeater to reduce such circulating currents, which are occasioned by impedance unbalances between the associated lines and their respective networks, to negligible proportions. This attenuation is under the control of voice-operated devices, which can redistribute the attenuation between the two sides of the repeater so that transmission through it in one direction or the other shall receive amplification, while transmission in the opposite direction is correspondingly attenuated. These voice-operated devices are actuated by telephonic currents reaching the repeater from the lines, and the direction in which gain is provided through the repeater is governed by the direction in which the telephonic currents are being transmitted.

It is well known that with the ordinary type of telephone repeater for use with two-wire lines, the gain that can be obtained is limited by the impedance balance between the lines to which the repeater is connected and the artificial lines or balancing networks which are provided, and which are intended to simulate the impedance of the lines. If at any frequency the impedances of the lines and their respective networks are dissimilar, a circulating current will flow within the repeater, the intensity of the current being determined by the degree of that impedance dissimilarity or unbalance, and by the gain of the repeater amplifying elements at that frequency. If the gain is not too great with respect to the impedance unbalance, any circulating currents which start to flow will be quickly damped out, and will produce no noticeable effects on the performance of the repeater. If, however, at any frequency the relation of unbalances and gains

is such that a circulating current once started receives a net increment in passing once through the repeater, such a current will build up to a point limited only by the power capacity of the amplifying elements, and a sustained oscillation will result. The repeater is then said to be in a singing condition, and is practically inoperative for transmission purposes. Even at gains somewhat lower than required to sustain such an oscillation, circulating currents of certain frequencies may be started by incoming waves, and may persist for an appreciable fraction of a second before being damped out. Under these conditions, serious distortion of transmitted speech will result.

To avoid these effects, it is customary to construct lines, with which repeaters are to be used, with great care to obtain a high degree of uniformity. The impedance characteristic of a line with uniformly distributed constants is such that it can be closely simulated, over a wide frequency range, by a comparatively simple network. Even a loaded line, in which inductance is inserted at periodic intervals, is not difficult to simulate over a considerable frequency range, provided the loading coils are all of substantially the same inductance, and are spaced at approximately equal intervals. At the higher frequencies, especially in the vicinity of the so-called cutoff frequency of a loaded line, accurate simulation becomes much more difficult, so that it is customary to reduce the gain of the repeater at these frequencies to avoid the possibility of singing.

Under some conditions it is impossible to obtain a satisfactory balance. For example, it may be necessary to use the repeater on a line which was not originally intended for such use, and which was therefore not constructed with particular care. Another example would be a repeater at a switching point, where connection must be made to any two of a considerable number of lines of different characteristics, and compromise networks must be used which will provide only a rough simulation for any of the lines. Under such conditions as these, our invention will permit a substantially greater effective gain than would otherwise be possible.

The invention will now be more clearly understood from the following detailed description of certain desirable embodiments thereof. The description is to be read with reference to the accompanying drawings, which indicates schematically the circuits and apparatus involved. Like reference characters designate like parts in the several figures of the drawing. Figs. 1, 2 and 3

represent different embodiments of the invention, each having certain advantages under particular conditions.

In each of the figures of the drawing, A and A' designate the telephone lines to which the repeater is connected, and B, B' the artificial lines or balancing networks which are intended to simulate approximately the impedance of the respective lines. C and C' are balanced transformers or hybrid coils as customarily used in this type of repeater, and D, D' indicate the amplifying elements of the repeater for the two directions of transmission. B, B', C, C', D and D', as interconnected by the heavy lines J, J', 5 and K, K' in Fig. 1, make up substantially the essential elements of a well known form of repeater.

To such a repeater we add amplifier-detectors E and E', responsive to telephonic currents, and 10 arranged to insert attenuation in one side or the other of the repeater. These amplifier-detectors may be of any well known type; they are indicated in Fig. 1 as including the familiar negative-grid type of vacuum tube detector, and in Figs. 2 15 and 3 as using a copper oxide or similar type of full-wave rectifier.

Returning to Fig. 1, the inputs of the amplifier-detectors E and E' are bridged across the conductors J and J', through the resistances H₁ 20 and H₁', respectively. The rectified output of E passes through winding L of relay F in the direction to operate that relay, and through winding M' of relay F' in such a direction as to oppose the operation of that relay. Similarly, 25 the rectified output of E' passes through winding L' in the direction to operate relay F', and through winding M in the direction to oppose the operation of relay F.

When no telephonic currents are reaching the 30 repeater, singing is prevented by the substantially equal attenuation elements H₂ and H₂', one in each side of the repeater. H₂ and H₂' are shown connected across conductors K, K' through the 35 transformers I and I', respectively; these transformers are provided because the circuit is carrying direct current. The circuit through H₂ is closed through the back contact of relay G, and similarly the circuit through H₂' is closed through the back contact of relay G'. These relays are 40 held against their back contacts by biasing current flowing through windings R and R' in series, as long as current does not flow through windings Q, P and Q', P', respectively, which windings are in the direction to operate the relays. 45 Windings Q and Q' are short-circuited by the back contacts, and windings P and P' are open-circuited at the front contacts of relays F and F' respectively. As long as relays F and F' are 50 normal, therefore, relays G and G' will also be normal, and losses H₂ and H₂' will both be connected to the circuit. Relay F is held against its 55 back contact when no telephonic currents are being received, by current from the plate battery in amplifier-detector E', flowing through winding M and variable resistance N to ground. None of 60 this current will flow through winding L under these conditions, since the detector tube is made nearly an infinite impedance by the large negative potential on the grid. Resistance N may 65 be adjusted to vary the sensitivity of relay M. Similarly, relay F' is held against its back contact by current from the plate battery of amplifier-detector E, through winding M' and resistance N' to ground.

If telephonic currents reach the repeater over

line A, a portion of them will enter E and be amplified and rectified. An increased current will then flow through winding M', increasing the bias against operation of relay F', and a portion of it will flow through winding L of relay F. If the incoming telephonic currents are sufficiently intense, relay F will operate. This removes the short circuit from winding Q of relay G, and closes the circuit through winding P; both of these windings then carry current in the direction for operation, and relay G will operate. The breaking of the back contact of relay G removes loss H₂ from the circuit. The closing of its front contact accomplishes two things; it connects resistance H₁' across conductors J', and it 10 short-circuits the input of amplifier-detector E'. The value of H₁' is so chosen as to introduce a loss in the circuit substantially equal to that which was removed by the disconnection of H₂. Singing of the repeater is thus prevented by the losses 15 H₁' and H₂', both in the lower side of the repeater, while the upper side of the repeater provides a net gain for the telephonic currents being transmitted from line A to line A'. The short-circuiting of E' prevents any portion of the voice currents which might be transmitted through coil C' into conductors J', due to unbalance between line A' and network B', from affecting E' and interfering with the proper operation of the device.

As long as telephonic currents are arriving from line A, relays F and G will remain operated, the telephonic currents will receive a net gain in passing through to line A', singing will be prevented by losses H₁' and H₂', and amplifier-detector E' will be disabled. As soon as the telephonic currents cease to arrive, relay F will release, since there is a steady biasing current flowing through winding M and resistance N. The circuit through winding P to ground will then be 20 broken, and winding Q will be short-circuited. The current through winding P will not immediately fall to zero, however, since it will be sustained by inductance S and condenser T. As long as this current remains greater than that 25 in the opposite direction through winding R, relay G will remain operated. Hence, by proper proportioning of inductance S, condenser T and resistance U to each other and to winding P, the speed of release of relay G can be controlled, 30 within limits. It is desirable that there should be a certain amount of delay in the release of relay G, since relay F may sometimes fall back between words, or even between syllables, and the effective gain should not be allowed to change 35 in this fashion. On the other hand, the release should not be made too slow, or complications 40 may arise if telephonic currents reach the repeater from the opposite direction before the relay releases. Thus, if the device is operated for 45 transmission from A to A', and telephonic currents arrive from A' while relay G is still operated, they will be unable to affect amplifier-detector E' because of the short circuit on its input. Such currents, will, however, be amplified 50 through D', and a portion of them will pass through coil C into conductors J, by reason of the unbalance between A and B. These currents can 55 then affect amplifier-detector E, and if of sufficient intensity may hold relay F operated, thus 60 maintaining the losses H₁' and H₂' in their own path.

If relays L and G release properly the circuit is then in a position to receive speech power from either direction; loss H₁' will be removed, and loss 65

H₂ inserted. Currents arriving from line A' will then operate the device in a manner exactly analogous to that already explained for currents arriving from A. Relays L' and G' will operate, 5 removing loss H₂', inserting loss H₁, and short-circuiting the input of amplifier-detector E. A net gain will thus be provided through the repeater in one direction or the other, according to the direction from which speech currents are arriving, 10 while sufficient loss to prevent singing is at all times maintained in the singing path.

In cases where the false operation referred to above may be serious, or where steady operation in one direction may be anticipated due to steady 15 noise on the lines, the circuit indicated in Fig. 2 of the drawing may be preferable. In this circuit the two relays F and F' are replaced by a single polarized relay designated as F. The operating windings L and L' of this relay are connected in 20 the output circuits of amplifier-detectors E and E', respectively, and are so wound that the fluxes due to currents in the two windings oppose each other. The arrangements for short-circuiting the input of one or the other of the amplifier-detectors are 25 omitted in this system, so that both of them are at all times sensitive to incoming telephonic currents. The direction of operation of relay F will therefore be determined by the direction of the net flux due to the opposing windings L and L'; 30 that is, by the winding which is carrying the stronger current. This in turn will depend upon the direction from which the more intense telephonic currents are reaching the repeater. Thus if the device is held in one direction by steady 35 noise on the circuit, the arrival from the other direction of speech currents of intensity greater than that of the noise will be sufficient to reverse relay F and give the gain of the repeater in the proper direction.

40 Inasmuch as a polarized relay of this type is not ordinarily capable of taking up a neutral position with its armature between the two contacts, it will not in general be feasible to provide a neutral condition corresponding to that of Fig. 1 when both relays F and F' are normal. Hence, 45 with this circuit the repeater is always set to give full gain in one direction or the other. Biasing windings V and V' are provided to hold the armature firmly against the contact in the direction 50 in which it is operated; each contact serves to short-circuit the one of these windings which tends to pull the armature in the other direction. Thus, when the relay operates in one direction, it remains so operated until telephonic currents arrive 55 from the other direction of sufficient intensity to overcome the biasing flux. The sensitivity of the device may be adjusted by varying the biasing current by means of resistances W and W'.

60 This adjustment can also eliminate the effects of differences in response of the two amplifier-detector units at low values of voice-frequency input, which are just sufficient to operate the relay. Thus the sensitivity of the device can be 65 made closely the same in the two directions. It is desirable to have a second adjustment for high values of input, since the differences between the amplifier-rectifiers may not be the same at high as at low inputs. Under these conditions, even 70 with proper adjustment at low inputs, false operation might be produced at high inputs. Such an independent adjustment is provided by means of the resistances X and X'. In practice, the device is preferably tested first at high inputs, and X and X' are given such values as to equalize any

differences between the two amplifier-detectors under these conditions. The input is then reduced to the value at which the device should just operate, and the current in the biasing windings V, V' is adjusted by means of resistances W, W' until the relay just operates on the desired value of input from either direction. This latter adjustment has virtually no effect on the performance of the system at high inputs. 5

In the position shown in the drawing, the armature of relay F is in the position resulting from the arrival of telephonic currents over line A. Winding Q' of relay G' is short-circuited by the ground on the armature of relay F, and relay G' is therefore held against its back contact by the 10 biasing current through relay R', which opposes operation. Relay G, on the other hand, is held 15 operated by current through winding Q, which overcomes the biasing flux due to the current in winding R. Loss H₂ is therefore disconnected from the circuit by the open back contact of relay G, while loss H₁' is connected in the lower side of the repeater through the front contact of the same relay. Loss H₂' is connected through 20 the back contact of relay G', and loss H₁ is disconnected through the open front contact of that relay. Thus, the repeater is in the position to 25 amplify speech traveling from A towards A', and will remain in this position, whether or not telephonic currents are arriving from line A, until 30 currents arrive from A' with sufficient strength to overcome the biasing flux due to the current in winding V, and cause the armature of relay F to move to its right hand contact. 35

When this occurs, the breaking of the left hand contact will remove the short circuit from biasing winding V', and from the operating winding Q' of relay G'. The current thus established through winding V' will assist in the movement 40 of the armature to the right, and will hold it firmly against the right hand contact when it arrives there. The current through winding Q' of relay G' will overcome the biasing flux due to winding R', and operate the relay, removing loss 45 H₂' and inserting loss H₁. Meantime, the arrival of the armature of relay F against its right hand contact short-circuits biasing winding V of relay F and operating winding Q of relay G. Relay G will therefore release, under the influence of the 50 steady biasing current through winding R. This will remove loss H₁' and insert loss H₂. The repeater is thus set to amplify speech traveling from A' towards A, and will remain in this position until the arrival of telephonic currents from A with sufficient intensity to reverse relay F. The 55 entire process will then be reversed.

In maintaining a device of this character, it is useful to be able to see at a glance whether or not it is operating approximately as it is intended to do. It is difficult to see the movement of the relay armatures, since this movement is very slight in relays of high sensitivity, and since they are ordinarily enclosed for protection against dust. We propose therefore to provide lamps Y, Y', 60 connected to the relay contacts as indicated, and so located as to be readily seen by the maintenance forces. When the armature of relay F is against its left-hand contact, as indicated in Fig. 2 of the drawing, lamp Y' is short-circuited through this contact, while lamp Y is lighted. 65 Conversely, when the armature is against its right-hand contact, lamp Y is short-circuited and lamp Y' is lighted. During an ordinary conversation, therefore, the light will pass from one lamp to the other several times a minute. If, 70 75

however, one lamp burns continuously for several minutes, the probabilities are that the device is failing to function as it should; and the maintenance man, observing such a condition, will proceed at once to investigate and determine whether trouble exists.

Since both amplifier-detectors are at all times sensitive to incoming telephonic currents, there is no possibility that noise will hold the device permanently in one direction, regardless of speech coming from the other direction. Speech currents will almost always have frequent peaks, due to vowel sounds, which are much more intense than steady noise currents on any commercial telephone circuit. These peaks will generally permit speech currents to take control of the device, even with considerable opposing noise, and to hold control of it, with the assistance of a very slight time lag in the operation of the relays, except perhaps during pauses between phrases. Furthermore, since the relays do not return to normal when no telephonic currents are flowing, there is no problem of adjusting time of release, as in the circuit of Fig. 1, and no possibility that speech from one direction can hold the device operated against itself, as explained in the discussion of that circuit.

In one respect the arrangement of Fig. 2 is definitely inferior to that of Fig. 1. If the repeater is set, for example, for transmission from A to A', voice currents arriving from A' which are too weak to operate relay F will suffer attenuation due to both H_1' and H_2' , instead of one loss only as in Fig. 1. Such currents will frequently include those due to initial consonant sounds in a word; the first vowel sound will usually have sufficient power to operate the relay. To minimize this effect, it will frequently be feasible to use attenuation elements which cause a comparatively low loss in the middle of the important voice-frequency range, and a greater loss at higher and lower frequencies. This is indicated in Fig. 2 by showing the attenuation elements as made up of a combination of resistance, inductance and capacity. This arrangement is particularly suitable when the repeater is to be used with loaded lines, since as mentioned in the foregoing general discussion, the unbalance between such a line and any simple form of network is usually much greater at the high frequencies, in the vicinity of the cutoff frequencies of the line, than at lower frequencies. The most suitable attenuation elements, therefore, would have a loss-frequency characteristic proportioned to the probable unbalance-frequency characteristic of the line or lines with which the repeater is to be used. Such attenuation elements could, of course, be used with the circuit of Fig. 1 as indicated by the nature of the pads H_2 and H_2' in that figure.

There is another advantage of using attenuation elements having a loss characteristic varying with frequency. As mentioned in the general discussion, it is customary to design telephone repeaters for two-wire lines so that their gain decreases at the higher frequencies, becoming zero at a point somewhat below the cutoff frequency of the lines with which they are to be used, since at that point no balance can be expected with any simple type of network. This is usually accomplished by inserting in each side of the repeater one or more sections of a low pass filter, whose cutoff point is somewhat below that of the line. These filters necessarily introduce a certain amount of distortion in the circuit. With the arrangement just explained, however, this loss

characteristic can be included in the attenuation elements, and the filter sections omitted from the repeater amplifiers, as indicated by the difference between amplifiers D, D', as shown in Fig. 1 and in Fig. 2. The distortion produced by these attenuation elements is, of course, confined to one side of the repeater; and the side which is amplifying speech currents is substantially free from distortion.

With the arrangement of Fig. 2, since the losses on one side of the repeater are either both in or both out at the same time, it is not essential that they be independently controlled, as in the circuit of Fig. 1. It will usually be desirable, however, to arrange that each amplifier-detector be connected at a point between the two loss elements, or, if they are combined into a single element, at a point where part of the loss of that element is on each side of the amplifier-detector. The reason for this is as follows. Suppose that losses H_2 and H_2' were omitted, and the entire attenuation necessary to keep the repeater from singing concentrated in H_1 and H_1' . The effect would be the same from the standpoint of transmission and singing, but false operation of the relays might result if one or both of the line unbalances were large. Thus, with the relays in the position shown in Fig. 2, suppose voice currents arrive from line A'. They receive the entire loss of the attenuation element before reaching the input of amplifier-detector E'. Beyond that point they receive the gain of amplifier D', and reach coil C at a considerably increased level, since loss H_2' has been removed and combined with H_1' . If the balance between line A and network B is low, there may be sufficient transmission through coil C to conductors J so that the level reaching the input of amplifier-detector E is equal to, or even greater than, that at the input of E'. Since transmission through the repeater is nearly instantaneous, there will be a current in winding L equal to or even greater than that in winding L', and relay F cannot reverse. Similar difficulties may exist if the loss elements are concentrated at any two symmetrical points on the two sides of the circuit.

Concentration of the losses into a single element for each side of the repeater will sometimes result in a desirable simplification in the relay system. Arrangements must, of course, be made to take care of the problem outlined in the preceding paragraph. Such a system is indicated in Fig. 3 of the drawing. This is preferable to the systems of Figs. 1 and 2 for simplicity and speed of operation, but lacks certain features of adjustability and reliability.

In Fig. 3, the losses are shown as series rather than shunt elements, and the entire loss on each side is inserted and removed by a single contact, so that the auxiliary relays G and G' of Figs. 1 and 2 can be omitted. Each loss is divided into two parts, H_1 , H_2 and H_1' , H_2' , respectively, to permit the connection of the amplifier-detectors at suitable intermediate points, as just explained. Control of the losses by a single relay is made possible by the use of a type of polarized relay in which the steady pull of the permanent magnet on the armature is sufficiently strong to hold the armature against the contact on either side to which it may be operated, without the assistance of auxiliary biasing current as in Fig. 2. It would not be feasible to connect the contacts of relay F in Fig. 2 directly to the loss elements,

as the battery for the biasing windings would cause clicks in the transmission circuit. The contacts of relay F in Fig. 3 can be so used, since the bias is obtained mechanically, as just explained. The sensitivity of the relay can be readily adjusted, as by varying resistances W and W' in Fig. 2.

The arrangement of Fig. 3 will have generally somewhat more tendency to objectionable effects due to chattering of the contacts of relay F under sudden heavy peaks of current from the amplifier-detectors. In the circuit of Fig. 2 such chattering will usually have no effect on the transmission, since relays G and G' will not operate or release instantly. In the circuit of Fig. 3, however, the chattering of the contact is applied directly to the loss element. This effect can be minimized by applying to the outputs of the amplifier-detectors E and E' the pairs of copper-oxide or similar rectifier units A₂ and A_{2'}, each pair connected in parallel opposition through transformers, as indicated. Each pair constitutes a full-wave rectifier with a negative resistance-voltage characteristic. The more intense the instantaneous peak of speech current, the greater will be the shunting effect of the rectifiers, while the low-intensity speech waves, which are just sufficient to operate the relay, will hardly be affected at all. The tendency to chattering will therefore be reduced.

With the armature of relay F in Fig. 3 against the left-hand contact, as shown, the repeater is in the condition established by telephonic currents arriving from line A. Losses H₁ and H₂ are both short-circuited by the left-hand contact of relay F, and losses H_{1'} and H_{2'} are both in the circuit to prevent singing. Amplifier-detector E' is connected across conductors J' at a point intermediate in the loss, the division of the loss being determined by the proportioning of H_{1'} and H_{2'} to each other and to the impedances of the line and of amplifier D'. Amplifier-detector E is effectively connected across conductors J through the impedance of H₁ and H₂ in parallel; by making the input impedance of E high in comparison with the impedances of H₁ and H₂, the effect of this on the sensitivity of E can be made small. The armature of relay F is held against the left-hand contact by the pull of the permanent magnet, as already explained.

On the arrival of telephonic currents from line A', winding L' of relay F will receive a larger current than winding L. If this differential is great enough to overcome the pull of the permanent magnet, the armature will be swung against the right-hand contact. Since the armature is now nearer to the right-hand pole-piece of the magnet than to the left-hand, the magnet will hold it in this position. The opening of the left-hand contact will insert losses H₁ and H₂ in the upper side of the repeater, and the closing of the right-hand contact will short-circuit losses H_{1'} and H_{2'}. The repeater will thus be set to amplify currents transmitted from A' towards A.

Transformers Z and Z' may be provided because the loss elements are inserted in one side only of conductors J and J', respectively. This arrangement results in series unbalance of conductors J and J', and if such unbalanced circuits were connected directly to lines A and A', noise might be produced if longitudinal induction were present on the line wires. Losses H₁ and H₂ must be placed in series in the same conductor if they are to be controlled by a single

relay contact; the same is true of losses H_{1'} and H_{2'}. The sensitive, high-speed polarized relays which are adapted to the type of voice-operated system described in this application cannot ordinarily be constructed with more than a single armature and two contacts.

While the invention has been disclosed in certain specific embodiments for the purposes of illustration, it will be understood that it may be embodied in other and different forms without departing from the spirit of the invention, which is defined in the appended claims.

What is claimed is:

1. In a two-way signaling system, the method of amplifying the signals at any point which consists in deriving at that point two separate unidirectional paths for transmission in the two directions, establishing a duplex balance against the line in each direction to reduce transmission from one path into the other, introducing the desired gain in one path, introducing in the other path an attenuation such that together with the effect of the duplex balances, it will prevent objectionable circulating currents through the two paths in tandem without causing substantially more loss than is necessary for that purpose, determining the direction in which signals are being transmitted by an electrical comparison between the intensities of the signal currents at corresponding points in the two paths, and interchanging the gain and loss between the two paths in accordance with the direction in which the signals are being transmitted.

2. In a telephone repeater for use on two-wire telephone lines, the method of obtaining from the repeater an effective gain in both directions greater than would be permitted by the balance existing between the connected lines and their corresponding networks, which consists in increasing the gain of the repeater in the direction in which telephonic currents are being transmitted and making a corresponding decrease in the gain in the opposite direction, the said direction of transmission being determined by a continuous electrical comparison between the intensities of the telephonic currents at corresponding points in the two halves of the repeater.

3. In a two-way telephone repeater having interconnected unidirectional paths for transmitting in the two directions, the method of obtaining an effective gain without introducing objectionable circulating currents within the repeater, which consists in introducing the desired gain in one of the paths, introducing in the other path sufficient loss at any frequency to prevent objectionable circulating currents within the repeater at that frequency, determining the direction of transmission of speech currents by a continuous electrical comparison between the intensities of those currents at corresponding points in the two paths, and interchanging the gain and the loss between the two paths in accordance with the direction of transmission so determined.

4. In a telephone repeater for use with two-wire telephone lines, two separate unidirectional paths for transmission in the two directions, an amplifying element in each path, a voice-operated device associated with each path and at all times responsive to telephone currents flowing therein, a switching system adapted to increase the gain of one or the other of the said amplifying elements and to make a corresponding decrease in the gain of the other

- amplifying element, means differentially connected to the two voice-operated devices and adapted to control the said switching system, and adjustable means so associated with the 5 said differential means and voice-operated devices as to make the operation of the said differential means dependent on the relative intensities of the telephonic currents affecting the two voice-operated devices.
- 10 5. In a two-way telephone repeater for use on two-wire telephone lines, two separate unidirectional paths for transmission in the two directions, an amplifying element with variable gain in each of the two paths, a voice-operated device associated with each path and at all 15 times responsive to telephonic currents flowing therein, means differentially connected to the two voice-operated devices for determining which of said devices is actuated by telephonic currents of the greater intensity, and means controlled by said differential means for making an increase in the gain of one of the amplifying elements and a corresponding decrease in the gain of the other amplifying element.
- 20 6. In a two-way telephone repeater for use on two-wire telephone lines, two separate unidirectional paths for transmission in the two directions, an amplifying element and an attenuation element in each of the two paths, a voice-operated device associated with each amplifying element, a relay controlled by each voice-operated device, a switching system controlled by each relay adapted to remove the attenuation element from the associated path and to insert 25 an additional attenuation element in the other path, means for adjusting the sensitivity of the said relays, and electrical means for adjusting the speed of operation and release of the said switching systems.
- 30 7. In a two-way telephone repeater for connection to two-wire telephone lines, two separate unidirectional paths for transmission in the two directions, an amplifying element in each path, an attenuation element associated with each path, each attenuation element providing sufficient loss at any frequency to prevent objectionable circulating currents through the repeater at that frequency, a voice-operated device associated with each path and at 35 all times sensitive to telephone currents reaching the repeater, and means differentially connected to the two voice-operated devices and adapted to insert one or the other of the said attenuation elements in the path whose direction of transmission is opposite to that in which telephonic currents are being transmitted in the connected lines.
- 40 8. In a telephone repeater for connection between two two-wire telephone lines, a network to balance each of said lines, a balanced transformer connected between each line and its corresponding network, the transformers being interconnected to form two transmission paths, a substantially distortionless amplifying element in each path, an attenuation element associated with each path and including resistance, inductance and capacity, each attenuation element having a loss-frequency characteristic, when inserted in the associated path, so proportioned to the unbalance frequency characteristics between the said lines and their respective networks as to prevent objectionable circulating currents at any frequency without causing a loss substantially greater than necessary for 45 that purpose, and voice-operated means for inserting one or the other of said attenuation elements in its associated path, said means being operated by telephonic currents reaching the repeater from the said lines, its direction of operation being determined by the direction of arrival of the said telephonic currents at the repeater.
- 50 9. In a telephone system, a two-way repeater connected between two two-wire telephone lines and provided with two substantially distortionless amplifying elements for amplification of telephonic currents in the two directions, voice-operated means for determining the direction in which telephonic currents are being transmitted through the system, and means controlled by the said voice-operated means for reducing the gain of one or the other of said amplifying elements at each frequency by an amount equal to, but not substantially exceeding, that necessary to prevent objectionable circulating currents through the repeater at that frequency.
- 55 10. In a telephone repeater for use with two-wire telephone lines, two separate unidirectional paths for transmission in the two directions, an amplifying element in each path, a voice-operated device associated with each path and responsive to telephonic currents flowing in that path, a polarized relay differentially connected to the two voice-operated devices in such a way that its direction of operation is determined by the relative intensities of telephonic currents affecting the two voice-operated devices, means controlled by the direction of operation of the said relay for inserting an attenuation element in one or the other of said paths, and electrical means also controlled by the direction of operation of the said relay for holding that relay in the direction last operated when no telephonic currents above a predetermined intensity are reaching the repeater from the lines.
- 60 11. In a telephone repeater for use with two-wire telephone lines, two separate unidirectional paths for transmission in the two directions, an amplifying element in each path, a voice-operated device associated with each path and responsive to telephonic currents flowing therein, a polarized relay differentially connected to the two voice-operated devices in such a way that its direction of operation is determined by the relative intensities of their output currents, adjustable means for proportioning the relative intensities of the output currents of the two voice-operated devices to the relative intensities of the telephonic currents flowing in the respective paths, and means controlled by the direction of operation of the said relay for inserting an attenuation element in one or the other of the said paths.
- 65 12. In a telephone repeater for use with two-wire telephone lines, two separate unidirectional paths for transmission in the two directions, an amplifying element in each path, a voice-operated device associated with each path and responsive to telephonic currents flowing therein, a polarized relay differentially associated with the two voice-operated devices in such a way that its direction of operation is determined by the relative intensities of the telephonic currents flowing in the two paths, means controlled by the direction of operation of the said relay for inserting an attenuation element in one or the other of the said paths, biasing means for holding the relay in the direction last operated, and means for so adjusting the said biasing means that a predetermined difference between the tele-

phonic currents in the two paths will be required to operate the said relay.

13. In a telephone repeater for use with two-wire telephone lines, two separate unidirectional paths for transmission in the two directions, an amplifying element in each path, a voice-operated device associated with each path and responsive to telephonic currents flowing therein, a polarized relay differentially connected with the two voice-operated devices in such a way that its direction of operation is determined by the relative intensities of the telephonic currents flowing in the two paths, means controlled by the direction of operation of the said relay for inserting an attenuation element in one or the other of the said paths, and visual means for indicating the direction in which the relay is operated.

14. In a telephone repeater, two separate unidirectional paths for transmission in the two directions, an amplifying element in each path, an attenuation element associated with each path, a voice-operated device associated with each path and at all times responsive to telephonic currents flowing in that path, and a polarized relay differentially connected to the two voice-operated devices in such a way that the direction of operation of the relay is determined by the relative intensities of the telephonic currents flowing in the said paths, the contacts of the relay being directly connected to the said attenuation elements in such a way as to remove one or the other of the attenuation elements from its associated path in accordance with the direction of operation of the relay.

15. In a telephone repeater, two separate unidirectional paths for transmission in the two directions, an amplifying element and an attenua-

tion element in each path, a voice-operated device associated with each path and responsive to telephonic currents flowing therein, a polarized relay differentially connected to the two voice-operated devices in such a way that its direction of operation is determined by the relative intensities of telephonic currents flowing in the two paths, the contacts of the relay being directly connected to the said attenuation elements in such a way as to remove one or the other of them from its associated path in accordance with the direction of operation of the relay, and magnetic means associated with the relay for holding the relay in the direction last operated when no telephonic currents above a predetermined intensity are flowing in the said paths.

16. In a telephone repeater, two separate unidirectional paths for transmission in the two directions, an amplifying element and an attenuation element in each path, a voice-operated device associated with each path and responsive to telephonic currents flowing therein, a polarized relay differentially connected to the two voice-operated devices in such a way that its direction of operation is determined by the relative intensities of telephonic currents flowing in the two paths, the contacts of the relay being directly connected to the said attenuation elements in such a manner as to remove one or the other of them from its associated path in accordance with the direction of operation of the relay, and means associated with each voice-operated device to limit the magnitude of the current flowing in the windings of the said relay.
